SHEET METAL EVAPORATOR

Edward M. Gaul, Evansville, Ind., assignor to International Harvester Company, a corporation of New Jersey

Application December 18, 1947, Serial No. 792,527

4 Claims. (Cl. 62—126)

1

This invention relates to evaporators or cooling units for refrigeration systems and more particularly to a structure of this character fabricated from sheet metal.

Heretofore evaporators of this type have been proposed which, although of complicated designs and expensive constructions, were not highly effective for heat transfer purposes. Since an evaporator must function primarily as a heat transfer device, it is, of course, highly desirable that this be accomplished in the most efficient manner.

It is a primary object of this invention, therefore, to provide a highly efficient sheet metal evaporator of greatly simplified design, that is, inexpensively constructed and yet is sturdy and compact.

It is another important object of this invention to provide an evaporator having a plurality of flat integrally formed refrigerated shelves, for supporting ice freezing trays and the like.

It is another object of this invention to provide an evaporator having high heat absorbing properties resulting from a unique arrangement of the construction thereof that permits thermal contact of substantially the entire bottom areas of ice freezing trays with flat refrigerated shelf surfaces fashioned within the evaporator.

A still further object is to provide a sheet metal evaporator wherein slugging of refrigerant flowing therethrough is avoided.

An additional object is to provide a sheet metal evaporator wherein, by a unique arrangement of the path of refrigerant flow therethrough, the maximum refrigerating effect is produced along the open or exposed side thereof adjacent the portion where the highest outside ambient temperatures are encountered.

Other objects and advantages will be understood and will become more apparent from the following description when read in conjunction with the drawings in which:

Fig. 1 is an elevation of the two proposed sheets from which the evaporator is fashioned, prior to bending;

Fig. 2 is a rear view perspective of the partially assembled evaporator;

Fig. 3 is a top elevation showing a completed embodiment of the invention;

Fig. 4 is a bottom view taken below the drip tray suspended beneath the evaporator;

Fig. 5 is a side elevation of the present invention;

Fig. 6 is a front end elevation of the present invention; and

2

Fig. 7 is an enlarged fragmentary sectional view of the structure shown within the circled area of Fig. 6.

Referring now to the drawings, numerals 10 and 11 indicate two metal sheets, preferably of stainless steel, formed with arcuate depressions in the surfaces thereof to provide liquid passages after the sheets have been superimposed or nested one upon the other as represented in Fig. 1. The first sheet indicated generally by the numeral 10 and consisting of integrally extending portions marked Top, Bottom and End is formed with longitudinally extending depressions 12 pressed only into the Bottom and End portions thereof, while the remainder or Top portion of said sheet is blank and non-depressed for reasons that will become apparent hereinafter. The second sheet indicated by the numeral 11 and similarly composed of a Top, Bottom and End section is provided with transverse convoluted depressions 13 pressed only into the top portion thereof with the remaining or Bottom and End portions blank and non-depressed. Sheet 10 is superimposed upon sheet 11 in such a manner that the blanked or non-depressed Top portion of sheet 10 mates and registers with the convoluted Top portion of sheet 11 to provide a continuous transversely extending liquid passageway 14, while the blanked or non-depressed Bottom and End portion of sheet 11 mates and registers with the depressed Bottom and End section of sheet 10 to provide longitudinally extending liquid passageways 15. One of the depressed passages so formed provides a passageway 16 for interconnecting said passageways 14 and 15. The marginal edges of these sheets, after being superimposed one upon the other, are secured together preferably by seam welding, while roller spot welds, indicated generally by the numeral 17, and, may, if desired be disposed at intervals along the non-depressed areas between the resulting passageways to prevent leakage of refrigerant between said passageways.

An enlarged transverse depression along one end of the indicated Bottom section of sheet 10 interconnects the longitudinal liquid passages 15 and provides a header 18 for uniformly distributing liquid refrigerant received through passage 16. At the opposite end of liquid passageways 15 a similar enlarged transverse depression connecting these passageways provides a header 19 which connects by means of smaller longitudinally extending passageways 20 with a similarly fashioned further header 21. At a point substantially midway between opposite marginal edges of sheet 10 in

the header 21 is an outlet connection 22 to which a suction line of the refrigerating system (not shown) may be connected. Likewise passageway 14 is provided with an inlet connection 23 for attachment to the conventional capillary tube inlet from the refrigerating system. After the two sheets 10 and 11 have been superimposed and fixedly secured together, the resulting plate assembly is bent along the broken lines (indicated in Fig. 1) to form the top, back and bottom of an evaporator positioned to resemble an overturned U-shape i. e. an assembly wherein the side legs of the U provide horizontally extending surfaces while the connecting leg provides a vertical wall connecting said horizontal surfaces together, indicated generally by the perspective shown in Fig. 2. It will be noted that the portion of the plate assembly indicated Top in Fig. 1 now becomes the top portion of the evaporator and that indicated End becomes the back wall, while the indicated Bottom becomes the bottom or lower portion of the evaporator. As now formed, the uppermost non-depressed surface of sheet 10 in the top portion provides a shelf 24 while the uppermost non-depressed surface of sheet 11 in the lower portion of the evaporator provides a shelf 25, both of which shelves have their entire upper surfaces flat and unobstructed, and thus are ideally suited to support ice-freezing trays and the like thereon in effective heat transfer relationship. The evaporator as formed is positioned in the refrigerating unit so that the open throat of the overturned U assembly forms a front opening through which access is had for the insertion or removal therefrom of ice-trays and the like.

To complete the enclosure of the evaporator, two vertical side wall sections indicated generally by the numeral 26 are provided. Since these wall sections are identical in construction, only one such wall element will be described in detail. Each such vertical side wall 26 is fashioned preferably from sheet metal and is provided along the upper marginal edge thereof with an inwardly turned supporting flange 27 which may be provided with any of the conventional mounting means for attachment to the interior wall of a refrigerating cabinet. Depending from the flange 27 is a vertical section 28, coextensive with the longitudinal depth of the evaporator, fashioned with two spaced apart ship-type flanges 29 and 30 adapted to provide guide channels 31 and 32 for supporting the shelves, 24 and 25 respectively, therein. Depending from the lower flange 30 is a section 33 having an outwardly extending U-shaped channel 34 whose outer marginal edge terminates in a semi-circular inverted channel 35. It will be understood that two such similar wall sections will be provided and will be positioned in complementary parallel relationship against opposed longitudinal marginal edges of the shelves 24 and 25. The channels 31 and 33 are each opened only enough to permit maintenance of a reasonably tight fit when pressed over the edges of the shelves 24 and 25. Fig. 7 shows this structure clearly in an enlarged detail.

A drip tray, slightly larger in outside dimensions than the bottom shelf of the evaporator and indicated generally by the numeral 36, is fashioned with a bottom portion 37 from which extends upwardly a front wall section 38, a rear wall section 39 and parallel side wall sections 40. The upper marginal edge of each side wall section 40 terminates in a semi-circular inverted channel 41 corresponding substantially to the

configuration of the supporting channel 35 which depends from each side wall section of the evaporator. The upper marginal edges of the front and back wall sections, 38 and 39 respectively, of the drip tray, and indicated generally by the numeral 42, should be of such height as to provide clearance and permit the tray to be slipped over and removed without interference from the supporting channel guides 35. The tray thus fashioned can be removed for emptying and other purposes by simply sliding it off its supporting channel guides 35. A drip tray of the character suitable for use with this embodiment of my invention may be fashioned from any suitable material. A preferred form involves sheet metal first stamped out and then bent to shape after which the vertical joints thereof may be secured in any conventional manner that will provide a substantially liquid-tight tray container. Such tray, however, may conceivably be fashioned from one of many suitable molding materials, such as the plastics or glass, and thus this feature of the invention is not limited to any specific material.

Slotted openings 43 spaced along the floor of the depending channel 34 are provided to permit moisture that accumulates on the side wall sections of the evaporator to drain into the drip tray 36. Since the outside dimensions of the drip tray 36 are sufficiently large to permit overlapping of the sides and back of the evaporator, it will be appreciated that any moisture accumulations coming off the evaporator will readily flow into the drip tray and thus prevent spoilage of any food located in the compartment which, in the conventional refrigerator, is generally positioned below the evaporator.

In operation, cold refrigerant enters the inlet opening 23, from a refrigerating system (not shown) and flows through the sinuous liquid passageway 14 into the conduit 16 and the header 18, whence it is distributed uniformly into the parallel longitudinally extending passageways 15. From the opposite end of these passages, the refrigerant is collected in a header 19 and directed through smaller passageways 20 into a second header 21 from which it is returned through the outlet connection 22 to the suction line of the refrigerating system. After the refrigerant enters from the refrigerating system, it is directed through the first transverse convolution of the passageway 14, positioned adjacent the opening of the evaporator where it encounters the highest temperatures while still in its coolest state. Since this first transverse convolution is substantially parallel with the evaporator opening, it will be appreciated that a substantially uniform temperature differential will be maintained across this opening. To further effectuate a uniform temperature differential, particularly across the lower portion of the evaporator, the refrigerant after completing its passage through the sinuous passageway 14 is directed by means of the passageway 16 into the header 18 where it is uniformly distributed transversely across the portion of the lower shelf 25 adjacent this opening. These characteristics effectuate highly effective heat transferring qualities, thus operating to provide a more efficient evaporator. In a refrigerating system of the character contemplated for use with evaporators of the type herein described, the refrigerant, during its flow through the evaporator, changes from a liquid to a gas, and, by the time it reaches the header 19, most of it has attained the gaseous state. Now, in order to as-

sure that the refrigerant is completely converted to a gas when it reaches the compressor, there is provided the second header 21. Connecting bleeder passageways 20, of slightly smaller diameter than the headers 19 and 21 tend to change the direction of flow of the refrigerant therethrough, and, by so doing, more time is provided to allow the evaporation of any liquid refrigerant which might remain at this point. As the refrigerant passes through the outlet connection 22 and into the return suction line to the compressor the direction of flow of said refrigerant is again changed, thus providing additional time in which to further effectuate complete evaporation. In this manner the refrigerant is effectively purged of any slugs before it returns to the compressor and the refrigerating cycle.

As previously described, the uppermost surfaces of both the upper and lower shelves, 24 and 25 respectively, are fashioned so that they are substantially flat and planar, and, since they are integrally formed and completely refrigerated, it will be appreciated that a simple and inexpensive means for incorporating a plurality of highly effective heat absorbing shelves, for supporting ice-freezing trays and the like, into a sheet metal evaporator has been provided.

Although only a preferred form of the invention has been illustrated, and that form described in detail, it will be apparent to those skilled in the art that various modifications may be made without departing from the spirit of the invention or from the scope of the appended claims.

What is claimed is:

1. An evaporator cooling unit for refrigerating systems, comprising: two sheet metal plates having depressions in each plate and superimposed one upon the other and fixedly secured together to provide continuous passageways for the passage of refrigerant therethrough, said plates being fashioned to provide a plurality of integrally formed planar surfaced horizontally disposed refrigerated shelves; inlet and outlet means for connection with a refrigerating system; side wall sections removably secured to said shelves; said side walls having depending means, including a U-shaped channel terminating in an inverted semi-circular channel member, adapted to support a moisture collecting container suspended therefrom.

2. An evaporator cooling unit for refrigerating systems comprising two sheet metal plates having depressions in each plate and superimposed one upon the other and fixedly secured together to provide continuous passageways for the passage of refrigerant therethrough, said plates being fashioned to provide a plurality of integrally formed planar surfaced horizontally disposed refrigerated shelves, inlet and outlet means for connection with a refrigerating system, side wall sections removably secured to said shelves, said side walls having a depending means including a U-shaped channel provided with a perforated floor therein and terminating in an inverted semi-circular channel member adapted to support a moisture collecting container suspended therefrom.

3. An evaporator cooling unit for refrigerating systems comprising, two sheet metal plates having depressions in each plate and superimposed one upon the other and fixedly secured together to provide continuous passageways for the passage of refrigerant therethrough, said plates being fashioned to provide a plurality of integrally fashioned planar surfaced horizontally disposed refrigerated shelves, inlet and outlet means for connection with a refrigerating system, side wall sections removably secured to said shelves, said side walls having depending means including a U-shaped channel member provided with a perforated floor therein and terminating in an inverted semi-circular channel member adapted to support in slidable relationship a moisture collecting container suspended therefrom, and a moisture collecting container having upwardly extending side wall portions terminating in inverted semi-circular channel sections adapted to be suspended in slidable relationship from said side wall members.
4. An evaporator cooling unit for refrigerating system comprising, two sheet metal plates having depressions in each plate and superimposed one upon the other and fixedly secured together to provide continuous passageways for the passage of refrigerant therethrough, said plates being fashioned to provide a plurality of integrally formed planar refrigerated horizontal shelf surfaces, inlet and outlet means for connection with a refrigerating system, a pair of vertical side wall sections adapted for removable affixment to opposed marginal edges of said shelves, said side wall sections having mounting means coextensive with their upper marginal edges and having spaced apart flange means adapted to snugly straddle the marginal edges of said refrigerated shelves and having integrally fashioned U-shaped channel sections provided with a perforated floor therein depending from the lower portion of said wall sections, said depending U channels having their outer marginal edges terminating in outwardly extending semi-circular inverted channels, and a moisture container having upwardly extending wall sections terminating in inwardly extending semi-circular inverted channels adapted to be suspended in slidable relationship with said outwardly extending channels of first said wall sections.
